UNITED STATES PATENT OFFICE.

MAX BLATT, OF DETROIT, MICHIGAN, ASSIGNOR TO ANNA BLATT, OF DETROIT, MICHIGAN.

ROLLING TELEPHONE-DIRECTORY.

1,273,722.

Specification of Letters Patent. Patented July 23, 1918.

Application filed October 5, 1917. Serial No. 194,848.

To all whom it may concern:

Be it known that I, MAX BLATT, a subject of the Czar of Bulgaria, residing at Detroit, in the county of Wayne and State of Michigan, have invented certain new and useful improvements in Rolling Telephone-Directories, of which the following is a specification.

This invention relates to advertising devices and has special reference to a telephone directory of the type which is adapted to be connected to a telephone stand of the ordinary desk or portable construction.

In the employment of devices for this purpose there has been used a spring actuated roller like a shade roller whereon a web of cloth or stout paper is rolled, the web receiving the names and telephone numbers of those persons with whom the owner of the device desires most often to communicate. It has even been found convenient to carry this roller on a bracket which is provided with an opening for the reception of the mouth-piece of the telephone transmitter so that by unscrewing this mouth-piece and placing the opening in proper position and again screwing the mouth-piece on, the device is securely attached to the telephone.

Such devices are more or less common but all of these devices have the demerit or defect of rendering it practically impossible to utilize both sides of the web which is on the roller for the information since the roller is fixed rigidly to the bracket and the latter in turn fixed rigidly to the telephone. Thus the information on the web is obtained by pulling down on the free edge of the web and exposing the front side. If an attempt is made to put information on the rear side of such web and read by turning up the web then the transmitter mouth-piece is covered.

The principal object of the present invention is to provide an improved instrument that either or both sides of the web may be used with equal facility.

With the above and other objects in view, as will be hereinafter apparent the invention consists in general of certain novel details of construction and combinations of parts hereinafter fully described, illustrated in the accompanying drawing, and specifically claimed.

In the accompanying drawing, like characters of reference indicate like parts in the several views, and:

Figure 1 is a perspective view showing the device as applied to an ordinary telephone.

Fig. 2 is a side view thereof, partly in section.

Fig. 3 is a longitudinal section through the shade roller and its housing or casing.

Fig. 4 is a section on the line 4—4 of Fig. 3.

In carrying out the objects of this invention and in the drawings hereunto attached there is disclosed a telephone having a transmitter mouth-piece and indicated in general at T. The device itself consists of a disk

10 having a centrally disposed opening 11 wherethrough passes the mouth-piece and this disk is furthermore provided around the major part of its periphery with a rolled edge 12 so that a card 13 may be held therein, the card being of course provided with an opening for the transmitter mouth-piece and displaying on its surface suitable advertising as may be printed in the spaces marked 14. The upper disk may also show the number of the user's telephone as at 15. The lower portion of the metal disk 10 is not beaded but has projecting therefrom a

downwardly and outwardly extending arm 16 which terminates at its extremity in a horizontal portion 17. Below the arm 16 is a metallic cylinder 18 having a slot 19

extending longitudinally of its lower part and having its ends closed by suitable caps 20. These caps 20 are provided with the proper openings for the reception of the pintles of an ordinary spring actuated shade roller 21, the same of course being smaller than the rollers used in windows. This metallic casing or housing 18 is connected to the horizontal portion 17 of the bracket by

a pivot 22 which forms a swivel so that the casing can be rotated in a horizontal plane and thus expose either side of a web 23 which is wound on the roller 21. On both

sides of this web 23 are to be printed or written the names of those people or companies with whom communication most frequently occurs. In order to manipulate the roller there is provided a finger pull 24

which is so arranged as to keep the lower 105 or free edge of the web straight and ex-

tends at all times in a position convenient to be grasped by the finger and thumb of the user. On the end of the shade roller is also provided the ratchet 25 and pawl 26 common in all such devices.

In operation it will of course be preferred to have the names arranged in such manner that one part of the alphabet as represented by the first letters of the names, 10 will occur on one side of the web while the remaining part of the alphabet will occur on the other. This is for convenience only. When so arranged the user simply grasps the finger grip 24 and pulls down upon the 15 web. This runs the web out of the casing and exposes the names on one side. In case the desired name is not found on the side exposed it is merely necessary to twist the casing around so that the other side of the 20 web is exposed with the remaining names which are thereon inscribed. Thus the device permits of the use of both sides of the web so that double the number of names can be placed on a web of equal size as is 25 possible where but one side only of the web is utilized.

There has thus been provided a simple and efficient device of the kind described and for the purpose specified.

30 It is obvious that many minor changes may be made in the form and construction of the invention without departing from the material principles thereof. It is not therefore desired to confine the invention to 35 the exact form herein shown and described but it is wished to include all such as properly come within the scope claimed.

Having thus described the invention, what is claimed as new, is:—

1. In a device of the kind described, the 40 combination with a bracket adapted for attachment to a telephone stand; of a spring actuated roller having swiveling connection intermediate its ends with the bracket, whereby the roller may be rotated to present the reverse side of a web carried thereon for observation, and a web on said roller having both sides adapted to receive desired data. 45

2. In a device of the character set forth, 50 a bracket comprising an arm having an opening to fit closely around a telephone transmitter mouth-piece, said arm extending away from a telephone stand upon application thereto and terminating in a horizontally disposed portion at its lower end, a tubular casing having a slot in its under side, a pivot connecting the tubular casing with the horizontal portion of the arm, a spring actuated roller housed in the casing, 55 a web wound on said roller and having its free end projecting through the slot, said pivot constituting means whereby the roller may be rotated to present either side of the web to observation, said web having both 60 sides arranged to receive information, and a finger grip on the free edge of said web. 65

In testimony whereof I affix my signature in the presence of two witnesses.

MAX BLATT.
